DESIGN FOR A FINGER RING

Georges Palisson, Houston, Tex., assignor to Star
Engraving Company, Houston, Tex., a corpora-
tion of Texas

Application March 2, 1934, Serial No. 50,915

Term of patent 3½ years

To all whom it may concern:

Be it known that I, Georges Palisson, a citizen
of the Republic of France, and residing at Hous-
ton, in the county of Harris and State of Texas,
have invented a new, original, and ornamental
Design for a Finger Ring, of which the following
is a specification, reference being had to the ac-
companying drawing, forming a part thereof.

Fig. 1 is a side view of the ring embodying the

design. Fig. 2 is a side view taken from the oppo-
site side from that shown in Fig. 1, and Fig. 3 is a
top plan view of the ring setting shown in Figs. 1
and 2.

I claim:—

The ornamental design for a finger ring, as
shown.

GEORGES PALISSON.
